UNITED STATES PATENT OFFICE.

JOE HENRY RICHARDS, OF DETROIT, MICHIGAN.

GAS-GENERATOR.

1,272,529.

Specification of Letters Patent. Patented July 16, 1918.

Application filed November 7, 1917. Serial No. 200,843.

To all whom it may concern:

Be it known that I, JOE H. RICHARDS, a citizen of the United States, residing at Detroit, in the county of Wayne and State of Michigan, have invented new and useful Improvements in Gas-Generators, of which the following is a specification.

This invention relates to improvements in acetylene gas generators, and refers more 10 specifically to a generator of that type wherein the carbid in granulated or pulverulent form is fed to a body of water in determined quantities automatically controlled by the pressure of gas generated.

15 In carrying out my invention it is my purpose to produce an acetylene generator of a simple, compact, strong and effective nature, wherein the generator or receptacle is arranged directly below the carbid hopper, while between the said tank and hopper is arranged a combined filtering and purifying chamber, pipe members leading therefrom to a combined gas reservoir and cooler, the house or outlet pipe being connected to 20 the said gas cooler and projecting through the water in an outer tank or receptacle; the bell being arranged directly above the carbid hopper is guided by suitable rollers which contact with the outer receptacle, the 25 bell actuating the valve for the carbid hopper whereby a determined amount of carbid will be automatically, and at desired intervals fed from the hopper to the generator tank.

30 It is a further object of the invention to produce an acetylene gas generator wherein the carbid hopper is provided with an auxiliary compartment controlled by a valve operative from the exterior of the machine, so 35 that when the main quantity of carbid in the hopper has been used, the carbid in the auxiliary compartment may be fed directly to the hopper, so that the necessity of refilling the hopper when gas is required for only 40 a comparatively small period, such as a single night, will not be necessitated and the labor and trouble of such refilling is thus effectively overcome.

45 It is a still further object of the invention to produce, in an acetylene gas generator, agitating means of a particular and effective nature arranged in the generator tank, but operative from the exterior of the device, so that all the particles of the carbid may be 50 agitated and broken up to produce the maxi-

mum amount of gas therefrom, and to reduce the residue in the generator tank.

Other objects and advantages will appear as the nature of the invention is more fully understood, reference being had to the accompanying drawings, in which,

Figure 1 is an approximately central vertical transverse sectional view through an acetylene gas generator constructed in accordance with this invention.

Fig. 2 is a horizontal sectional view approximately on the line 2—2 of Fig. 1.

Fig. 3 is a horizontal sectional view approximately on the line 3—3 of Fig. 1.

Fig. 4 is a sectional view approximately on the line 4—4 of Fig. 1.

Fig. 5 is an enlarged, approximately central longitudinal sectional view through the carbid hopper and the upper portion of the bell showing the latter actuating the valve 75 at the outlet mouth of the hopper to open the said valve.

Fig. 6 is a horizontal sectional view approximately on the line 6—6 of Fig. 5.

Fig. 7 is a perspective view of the filtering and purifying device.

Fig. 8 is a perspective view of one of the collars designed to be arranged upon the pipes between the cooling chamber and the purifying chamber for supporting the floor 85 or table on which the generator tank rests.

Fig. 9 is a perspective view of the agitator, and

Fig. 10 is a transverse sectional view through the carbid hopper, looking toward 90 the door therein.

In carrying out my invention, I propose to bury the water tank 10 in the ground, at a suitable distance from the residence supplied with the gas, and, of course, at a suitable distance from other houses or out buildings. The mouth of the tank 10, however, is projected a suitable distance above the ground, and the mouth of the said tank is normally closed by a flanged cover 11, the 95 same being provided with suitable handles 12, whereby the cover may be removed so that access to the interior of the tank may be obtained. The water level in the tank is indicated by the numeral 13, the said water providing a seal between the gasometer bell and the generator tank of the construction.

Arranged in the bottom of the tank 10 is a chamber 14 the periphery of which being preferably round to agree with the round 110

cross sectional contour of the tank 10, and connected with this chamber 14 and extending upwardly therefrom, is a plurality of pipes 15, preferably four in number. The 5 pipes 15 communicate with the lower wall of the purifying receptacle 16, and retain the said receptacle at a proper spaced relation with respect to the chamber 14. The receptacle 16 comprises an inner and an outer 10 wall, 17 and 18 respectively, the said walls being round in cross section and being connected, at their lower edges by a preferably integral member indicated by the numeral 19. Between the walls 17 and 18 is packed 15 a combined purifying and filtering medium indicated by the numeral 20, and the inner wall 17 is in the nature of a reticulated member, so that gas from the generator tank may pass through the openings 21 therein, 20 causing the said gas to be filtered and purified by circulating through the packing 20 and thereafter to be delivered through the pipes 15 to the chamber 14. The chamber 14 being at all times immersed in the water in 25 the tank 10 is retained in a cooled state, and consequently, the gas stored in the said chamber 14 will be likewise cooled.

The inner wall 17 of the purifying and filtering receptacle 16 extends a suitable distance 30 below the connecting plate or wall 19 for the inner and outer walls of the said receptacle, the projecting portion, however, is not provided with openings, the same being indicated by the numeral 22, and this extension or annular flange 22 is designed to be received in and to frictionally engage with the upper or mouth portion of the generator tank 23. The tank, adjacent the upper or mouth end thereof, but at a suitable distance 35 below the connection therewith with the flange or extension 22 is provided with one or more outlet openings 24, the level of the water in the said tank is indicated by the numeral 25 and is below the openings 24, but above the level 13 of the water in the 40 tank 10. The generator tank has its bottom resting upon a floor or platform 26, the same having spaced openings through which the pipes 15 pass, and the table or 45 platform 26 is retained at a proper horizontal position upon the said pipes 15 by a plurality of collars 27 arranged one around each of the pipes 15, each of the said collars being sustained upon the respective pipes 15 50 through the medium of binding elements, such as screws or bolts 28.

Arranged centrally and extending vertically through both the platform 26 and the bottom of the generator tank 23 is a tube 29, the said tube being additionally supported in a sleeve 30 secured to the bottom of the generator tank as well as to the said sleeve and passing through the sleeve 29 is a rod 31. This rod, at the upper end thereof, 55 which extends a suitable distance above the

tube 29, is provided with a head 32, rod members 33 being secured to the said head and depending therefrom and to the ends of these rods 33 is secured the agitator 34. The agitator preferably comprises a member having a flat round periphery provided, upon its inner edge, with inwardly extending right angularly arranged lugs, two of the diametrically opposite lugs indicated by the numerals 35, being preferably in the 70 nature of flat plates having openings adjacent the inner ends thereof which receive the ends of the rods 33, and the said rods are pivotally connected to the said lugs 35, preferably through the medium of removable 75 elements such as cotter pins 36. The remaining inwardly extending members or lugs, indicated for distinction by the numerals 37 have central elongated openings, and the said members 37 may be formed each 80 with a single piece of flat metal bent to comprise parallel arms which have their ends connected with the periphery of the annulus or ring member 34 and their outer or connecting portions rounded, as clearly illustrated in Fig. 9 of the drawings. The spaced arms of the members 37 assist in turning the water in the generator tank and in contacting with carbid in the said tank, will break the same, thus permitting the generation of a maximum amount of gas from the carbid, and at the same time reducing the residue in the generator tank.

One of the collars 27, illustrated in detail in Fig. 8 of the drawings, is provided, 100 upon one of its sides with a depending strap 38 which has its lower end bent upon itself providing an outer arm 39, and between this arm 39 and the strap 38 is pivotally secured a lever 40, the said lever having its inner end loosely connected with the rod 31, and its opposite end loosely connected with the vertically extending agitator operating rod 42, the said rod 42 being arranged in close proximity to the inner wall of the tank 10 105 and terminating a suitable distance below the cover 11, the outer end of the said rod 42 being bent upon itself to provide a handle 43, whereby the said rod may be easily reciprocated to reciprocate the agitator 34. 110 The rod 42 may, if desired, be guided through suitable bearing eyes 44, in the tank 10.

The upper and open end of the purifying receptacle 16 is closed by a flat disk-like 120 plate 45, the same having its inner periphery formed with or secured to a cross sectional round member or sleeve 46 which projects above and a suitable distance below the plate 45 so that the lower projecting portion of the said sleeve 46 will frictionally contact with the upper surface of the inner wall 17 of the receptacle 16 above, however, the upper row of openings in the said wall 17. The upper end of the sleeve 46 is flared 130

outwardly and upwardly as at 47, and the substantially cone-shape lower end 48 of the carbid hopper 49 rests upon the flared mouth 47 of the sleeve 46, and may be secured there-
5 to if desired.

The outlet mouth 50 for the carbid hopper 49 is normally closed by a flat valve 51, and the said mouth 50 is surrounded by an annular member 52 secured or formed with
10 the carbid hopper 49, the said member 52 providing a directing flange for the carbid when the valve 51 is open and the said carbid delivered therefrom to the generator tank 23. The sleeve 46 is provided with an
15 opening 53 through which freely passes a lever 54, the same also passing through an opening in the directing flange 52 and being pivoted to the said flange as at 55. The inner end of the lever 54 is loosely connected
20 to the rod 56 of the valve 51, the said rod 56 being extended in both directions from the said valve 51, and the outer end of the rod 56 passes through a central opening 57 in the closed top of the carbid tank 49. The
25 top of the carbid hopper 49 is provided with an opening surrounded by a threaded flange 58, the said flange being engaged by a screw cap 59, and carbid is fed in the hopper through the said opening.

Surrounding the hopper, and the purifying receptacle and having its lower and open end at all times received in the water in the tank 10 is the gasometer bell 60. Upon the closed top of the bell 60 is secured suitably spaced, outwardly extending arms 61 which preferably have their outer ends bifurcated to receive rollers 62 which are journaled in the said bifurcated ends of the arms, and these rollers frictionally
30 engage with the inner surface of the tank 10, whereby to guide the bell in its vertical movement as well as to retain the said bell in a proper position in the tank 10. The upper and closed end of the bell 60 is provided with an opening receiving a pet-cock 63 and this cock is designed to be opened, when the carbid hopper 49 requires refilling, to permit of the escape of accumulated waste
35 gas.

From experience, I have found that not infrequently and at undesirable hours in the night, all of the carbid from the hopper has been used, and, consequently, must be recharged before additional gas can be generated. The trouble, inconvenience, and danger of recharging a gas machine of this character in the night is well known to those using such machines, and to overcome this, I arrange in the carbid hopper 49,
40 upon two of the diametrically opposite walls thereof, vertically extending cleats arranged in pairs, as indicated by the numerals 64. I arrange between these cleats 64, for vertical movement, a door or valve 65 so that
45 the portion of the hopper between the door

or valve 65 and the wall adjacent the said valve provides an auxiliary carbid chamber 66. The lower edge of the door 65, of course, is shaped to snugly engage with the conical lower end 48 of the hopper 49, and
50 loosely connected centrally to the upper edge of the door 65 is a rod 67 which passes through a suitable opening in the upper wall of the hopper. The said upper wall has arranged thereon, an outwardly extending
55 lug 68 to which is approximately centrally pivoted a lever 69, the said lever being loosely connected to the upper end of the rod 67, and the outer end of the said lever 69 has pivotally connected therewith, the
60 inner arm 70 of an operating member 71. The operating member for the door 65 is preferably in the nature of a rod, bent upon itself to provide inner and outer parallel arms, the outer arm terminating a suitable
65 distance above the gas bell in the mouth of the tank 10 and being provided with a suitable knob or handle 72, whereby the lever 69 may be rocked to open the door 65 and to permit of the surplus or additional carbid
70 in the compartment 66 entering the hopper 49, the said carbid, as stated, being sufficient to permit of the generation of gas for a
75 determined interval.

Connected with the cooling and reservoir
80 chamber 44 is the house pipe 74, the same being arranged outwardly of the bell 60 and having its upper end provided with an angular extension 75, the pipe extension 75 being preferably buried in the ground a distance below the frost level, the main pipe
85 75 being, of course, connected with the usual branch pipes leading to the various fixtures in the house.

It is believed the operation of the device
90 will be perfectly apparent to those skilled in the art to which such inventions appertain, the surplus gas from the generator tank 23 escaping through both the openings 24 and 53 and entering the bell 60, causing
95 the said bell to rise. As the gas is used, the pressure thereof upon the bell 60 is, of course, decreased, so that the bell descends and contacting with the upper end of the valve rod 56 will open the valve 51, the
100 said valve being normally held in its closed position by a weight 76 secured upon the outer end of the lever 54, and this weight, of course, returns the valve to its seated position when gas is again generated to
105 cause the bell 60 to rise.

Having thus described my invention, what I claim is:

1. In an acetylene gas generator, a water tank, a carbid hopper in said tank, a weight
110 controlled valve closing the outlet mouth of the hopper, a stem for said valve extending through the hopper, a purifying receptacle arranged below the hopper, and including a member having an inner per-
115

forated wall, a sleeve on the purifying receptacle engaging with the hopper for retaining the said hopper spaced from said receptacle, a generator tank below the purifying receptacle and frictionally engaging therewith, and said tank having an opening above its water level, a cooling chamber below the generating tank, pipe members between the chamber and the purifying receptacle, means on said pipes supporting the generator tank, an outlet pipe also communicating with the chamber, a bell surrounding the carbide hopper and purifying receptacle, and having its open end received in the water in the first mentioned tank, and anti-frictional guiding elements between the bell and the water tank.

2. In an acetylene gas generator, a water tank, a carbide hopper in said tank, a weight controlled valve closing the outlet mouth of the hopper, a stem for said valve extending through the hopper, a purifying receptacle arranged below the hopper, and including a member having an inner perforated wall, a sleeve on the purifying receptacle engaging with the hopper for retaining the said hopper spaced from said receptacle, a generator tank below the purifying receptacle and frictionally engaging therewith, and said tank having an opening above its water level, a cooling chamber below the generating tank, pipe members between the chamber and the purifying receptacle, means on said pipes supporting the generator tank, an outlet pipe also communicating with the chamber, a bell surrounding the carbide hopper and purifying receptacle, and having its open end received in the water in the first mentioned tank, anti-frictional guiding elements between the bell and the water tank, an auxiliary compartment in the carbide hopper, a door closing the same, and means, including a substantially U-shaped member having its arms disposed to the opposite sides of the bell for operating the said door.

3. In an acetylene gas generator, a water tank, a carbide hopper in said tank, a weight controlled valve closing the outlet mouth of the hopper, a stem for said valve extending through the hopper, a purifying receptacle arranged below the hopper, and including a member having an inner perforated wall, a sleeve on the purifying receptacle engaging with the hopper for retaining the said hopper spaced from said receptacle, a generator tank below the purifying receptacle and frictionally engaging therewith, and said tank having an opening above its water level, a cooling chamber below the generating tank, pipe members between the chamber and the purifying receptacle, means on said pipes supporting the generator tank, an outlet pipe also communicating with the chamber, a bell surrounding the carbide hopper and purifying receptacle, and having

its open end received in the water in the first mentioned tank, anti-frictional guiding elements between the bell and the water tank, an auxiliary compartment in the hopper, a door closing the same, means, arranged adjacent the mouth of the water tank for operating the said door, a vertically movable agitator in the generator tank, and means operable from the mouth of the water tank for operating the agitator.

4. In an acetylene gas generator, a water tank designed to be buried in the ground, a flange cover closing the mouth of said tank, a carbide hopper in the tank, a weight controlled door normally closing the mouth of the hopper, a stem for the valve extending through the top of the hopper, oppositely disposed spaced cleats in the hopper, a door arranged between said cleats, whereby to provide an auxiliary carbide receptacle in the hopper, means operative from adjacent the mouth of the water tank for sliding said door, a sleeve having a flange end receiving the lower portion of the hopper, a directing flange upon the said lower portion of the hopper surrounding the outlet thereof, a purifying receptacle frictionally engaged by the sleeve, said receptacle including inner and outer walls, the inner wall being reticulated, a gas cooling chamber resting upon the bottom of the water receptacle, pipes between said chamber and the purifying receptacle, adjustable collars on said pipes, a platform resting on said collars, a generator tank supported on said platform and frictionally engaging with the purifying receptacle, said generator tank having an opening above the water line therein, a supply pipe connected with the cooling chamber, a bell surrounding the hopper and purifying receptacle and having its lower end below the water line in the water receptacle, anti-frictional guide members between the bell and the water receptacle and the pet-cock at the outer closed end of the bell.

5. In an acetylene gas generator, a water tank, a cover for the mouth thereof, a carbide receptacle having a lower cone-shaped end in the tank, a flat weight influenced valve closing the mouth of the hopper, a stem for said valve projecting through the closed top of the hopper, a purifying receptacle arranged below the hopper and comprising inner and outer spaced walls, a connecting member for the lower edges of the said walls, the inner wall being reticulated, and a filtering substance packed between the inner and outer walls of the said receptacle, a disk resting upon the outer edge of the tank and closing the open end thereof, a sleeve connected with said disk frictionally engaging with the inner wall of the receptacle at the upper portion thereof, said sleeve also engaging with the conical end

- of the hopper, a directing flange surrounding the valve of the hopper, a cooling chamber on the bottom of the tank, pipe members between said chamber and the purifying receptacle, an adjustable platform supported on the pipes, a generator tank having water therein resting upon the platform, a depending flange on the purifying receptacle frictionally engaging the mouth 5 of the generator tank, said tank having an opening above the water level therein, and the water level in the said tank being above the water level connected with the cooling chamber, an agitator in the generator tank, 10 and means, operative from the mouth of the water tank for vertically reciprocating the agitator, a bell surrounding the hopper and the purifying receptacle and having its open end below the water line in the water 15 tank, and anti-frictional guide means between the bell and the water tank.
6. In an acetylene gas generator, a water tank, a carbide hopper therein, a weight influenced valve normally closing the mouth 20 of the hopper, a stem for the valve extending through the top of the hopper, a bell surrounding the hopper and having its open end received in the water of the water tank, a handle for the bell, a purifying receptacle 25 having an inner reticulated wall below the 30 hopper, a member frictionally engaging with the receptacle and contacting with the hopper for retaining the same spaced, a cooling chamber in the bottom of the tank, pipe members between said chamber of the purifying receptacle, a platform adjustably secured on said pipes, a generating tank supported on said platform and having its open mouth frictionally engaging with the purifying receptacle, said generating tank having 35 an opening above the water line therein, a sleeve extending vertically through the bottom of the generator tank and through the platform, a rod movable through said sleeve, a head upon the upper end of the 40 rod, rod members depending from the head, an agitator comprising a ring member having inturned lugs connected with the said rods, a lever pivotally connected with one of the sustaining members for the platform, 45 and with the rod passing through the sleeve and an operating rod movable through guides in the water tank and having its end provided with a handle disposed adjacent to the mouth of the said water tank. 50
- In testimony whereof I affix my signature.

JOE HENRY RICHARDS.
